UNITED STATES PATENT OFFICE.

FRANCIS DE GORDY, OF PROVIDENCE, RHODE ISLAND.

TOP FOR FLASKS.

SPECIFICATION forming part of Letters Patent No. 684,641, dated October 10, 1899.

Application filed February 9, 1899. Serial No. 705,098. (No model.)

To all whom it may concern:

Be it known that I, FRANCIS DE GORDY, of Providence, in the county of Providence and State of Rhode Island, have invented a new and useful Improvement in Tops for Flasks; and I hereby declare that the following is a full, clear, and exact description of the same, reference being had to the accompanying drawings, forming part of this specification.

The metal tops for flasks are usually secured by a hinge-ring to the neck of metal flasks or to a metal sleeve secured to the neck of a glass or other flask. These metal tops have heretofore been made of a number of parts which were secured to each other by solder. The cup in which the cork is held was soldered to a sleeve on which the hinge-ring turned, and a sleeve provided with the projecting screw-thread sections and having a flange at the lower end was secured by solder or brazing in the ring-sleeve. This construction is expensive and the top so made is weak, the soldered joints forming a number of weak points.

The object of this invention is to secure a more durable and a cheaper flask-top; and to this end the invention consists in the peculiar and novel construction whereby the flask-top is made complete out of one piece of sheet metal without the use of solder or brazing, as will be more fully set forth hereinafter.

Figure 1 is a side view of a cup drawn up from sheet metal; and Fig. 2 is a sectional view of the same, illustrating the first step in the manufacture of the flask-top. Fig. 3 is a sectional view showing the next step in the manufacture of the flask-top. Figs. 4 and 5 are sectional views illustrating the next successive steps, and Fig. 6 is a sectional view of the completed flask-top. Fig. 7 is a side view showing a flask provided with the improved top, and Fig. 8 is a sectional view of the same.

In the construction of my improved flask-top I form the cup (shown in Figs. 1 and 2) from a sheet-metal blank and then by spinning the metal cup produce the head *a*, as shown in Fig. 3, and continuing the spinning form the annular bead *b*, as shown in Fig. 4,

and the sleeve *c*. I now place on a suitable die and with a contractile outer die force the metal forming the inclined ways *d d* inward. The hinge-ring *e* is now placed over the sleeve *c*, and the lower edge of the sleeve *c* is burnished or spun outward to form the flange *f*. The hinge-ring is thus secured to the top between the bead *b* and the flange *f*, so that the top may freely turn in the ring *e*. The cork *g* is now pressed into the head *a* of the top, and the hinge-ring *e* is secured to the hinge on the neck *h*.

A top for flasks constructed in this manner is much more durable than one constructed in parts and soldered or brazed together. As the metal is not subjected to heat in soldering, it is stiffer and stronger. The top is secured to the neck by passing the latch *i* of the neck in between the inclined ways *d d* and rotating the head so as to draw the cork *g* onto the end of the neck, thereby closing the outlet.

Having thus described my invention, I claim as new and desire to secure by Letters Patent—

In a top for flasks, the combination with the metal neck secured to or forming part of a metal flask, of inclined ways formed on the contracted upper portion of the metal neck, the part of the hinge projecting from one side of the metal neck, and a ring provided with a hinge portion pivotally secured to the hinge portion on the metal neck, of the head portion of the top consisting of the head *a*, the annular outwardly-projecting bead *b*, the sleeve *c*, the inclined ways *d d*, the flange *f* formed out of one integral piece of sheet metal in the manner described, and the cork within the head; whereby the head may be rotated within the ring and secured to close the flask, the strain being exerted on the integral metal of the head, as described.

In witness whereof I have hereunto set my hand.

FRANCIS DE GORDY.
